DYNAMOELECTRIC MACHINE

John W. Clokey, Pittsburgh, Pa., assignor to Westinghouse Electric Corporation, East Pittsburgh, Pa., a corporation of Pennsylvania

Application September 8, 1950, Serial No. 183,761

4 Claims. (Cl. 171—252)

1

My invention relates to the stator-construction of salient-pole dynamo-electric machines. It relates to the mounting of the salient-pole-pieces, with winding-coils in place, on an initially flat thin flexible magnetizable mounting-sheet or plate, which is subsequently wound into a cylindrical form. The around-the-frame winding-connections for the coils may be completed either before or after the cylindrical bending of the mounting-plate—usually after—and then the salient-pole assembly which is thus formed can be dipped and baked or otherwise treated to improve the insulation, and tested, before said assembly is inserted into the bore of the rigid stator-frame, where it is secured in place by a suitable number of pole-bolts which pass in through the stator-frame.

My invention is particularly applicable to railroad-motors, for traction or auxiliary purposes, and it is particularly applicable to frames which are cylindrical in shape, although, theoretically, at least, my invention could be applied to non-cylindrical frames. As a result of my invention, the railroad (or other user of the machine) can more quickly rewind a traction-motor, for example; and a repair-shop which is not fully equipped to wind and treat a large-sized frame might easily install a stator-insert in accordance with my invention.

An exemplary form of embodiment of my invention is illustrated in the accompanying drawing, wherein

Figure 1 is a perspective view of a part of a flat flexible mounting-sheet or plate, with some of the poles and coils underneath it;

Fig. 2 is a perspective view of the same thing, turned upside down;

Fig. 3 is an end-view of a drum which is used for winding the stator-insert into a cylindrical shape;

Fig. 4 is an end-view of a completed rolled stator-insert, and

Fig. 5 is a fragmentary longitudinal sectional view of a traction-motor, showing my stator-insert in place in the machine.

As shown in Fig. 5, the complete dynamo-electric machine comprises a salient-pole stator-member 6, and a rotor-member 7 mounted for rotation therewithin. While my invention was designed, and is particularly adapted, for traction-motors, it is obviously adapted to other types of dynamo-electric machines. The rotor-member 7 is illustrated as being of a type having a commutator 8. In accordance with my invention, the stator-member 6 is made of two separable parts,

2

namely a substantially rigid magnetizable frame 10, and a stator-insert 11, such as is shown in Fig. 4. The frame 10 has an axially extending opening 12 therein, preferably in the form of a cylindrical bore. The outer periphery of the stator-insert 11 has a configuration suitable for fitting within said frame-opening or bore 12, so that the stator-insert can be removably retained within the frame 10 by means of pole-bolts 13 passing radially through the frame.

In accordance with my invention, the stator-insert consists of a relatively thin flexible magnetizable mounting-plate 15, which encircles a plurality of salient pole-pieces, which may include main poles 17 and commutating-poles 18 which carry their usual coils 17C and 18C.

In the initial assembly of my stator-insert 11, the mounting-plate 15 is flat, as shown in Figs. 1 and 2, and the salient pole-pieces 17 and 18 are 20 removably bolted thereto, with the coils in place, as shown at 19 in Fig. 1. The stator-pole assembly is then wound or bent into a cylindrical shape (or other shape necessary to fit within the frame-opening 12). A convenient tool for assisting in this bending-operation is shown in Fig. 3 in the form of a hollow cylindrical drum 21, which preferably has outwardly extending threaded pins or bolts 22 therein, for engaging in corresponding poles 23 in the several commutating-poles 18, as shown in Fig. 2, so as to assist in centering said commutating-poles, which are relatively narrow in a circumferential direction. The pins 22 are then removed from the inside of the drum 21, so that the drum can be removed from inside of the cylindrically shaped salient-pole assembly.

As shown in Fig. 4, the stator-coils 17C and 18C are provided with suitable around-the-frame winding-connections 24, which are made either 30 before or after the bending operation—usually after said operation, in a large-sized machine in which the connections are quite stiff.

The stator-insert 11 is now complete, as shown in Fig. 4. It can now be easily handled, both 40 for completing the coil-connections 24, and for any necessary dipping and baking for treating the insulation on the windings, and for all necessary testing, after which the finished stator-insert 11 may be slipped into the bore 12 of the stator-frame 10, and secured in place by the pole-bolts 13 in the frame.

It will be noted that my invention makes it possible to assemble the various salient pole-pieces of the machine on a flat plate 15, as shown in 50 Figs. 1 and 2, thereby facilitating the assembling

operation, including both the pole-pieces and the coils which surround them. The plate 15 is very thin and flexible, so that there is no difficulty at all in winding the salient-pole assembly into a cylindrical confirmation, or any other confirmation necessary for fitting the stator-frame 10. The completed stator-insert 11, as shown in Fig. 4, is appreciably smaller than the thick heavy stator-frame 10, so that the stator-insert can be more easily handled, in shops which are limited as to the maximum outer diameters of members which can be handled.

From the standpoint of the customer, a motor having a damaged stator-winding can be easily repaired by removing the pole-bolts 13 and slipping the entire stator-winding assembly 11 out of the frame 10, and inserting a new stator-winding assembly, while the old one is being repaired.

In my invention, the flexible mounting-plate 15 is quite thin. It is made of magnetizable material, so that it forms a part of the flux-carrying frame or yoke of the machine. Since this plate is quite thin, old motors which had their salient pole-pieces directly bolted to the heavy stator-frame 10 can be converted to my new type by boring the old frames slightly oversize, in order to accommodate the new stator-winding assembly. This permits treating and testing the stator-winding assembly, independently of the frame.

While I have shown only a single illustrative form of embodiment of my invention, I wish it to be understood that I am not limited to the illustrated details of construction. I desire,

therefore, that the appended claims shall be accorded the broadest construction consistent with their language.

I claim as my invention:

1. A dynamo-electric machine having a salient-pole stator-member, and a rotor-member therewithin, said stator-member being characterized by having a substantially rigid frame having an axially extending opening therein, and a pole-assembly removably secured within said opening, said pole-assembly comprising a relatively thin flexible magnetizable mounting-plate, salient pole-pieces secured to said mounting-plate, coils carried by said pole-pieces, and around-the-frame winding-connections for said coils, said mounting-plate fitting within said opening in the frame.

2. The invention as defined in claim 1, characterized by said frame being cylindrical, and its opening being a cylindrical bore.

3. A removable pole-assembly for the stator-frame of a dynamo-electric machine, characterized by having a relatively thin flexible magnetizable mounting-plate, salient pole-pieces secured to said mounting-plate, coils carried by said pole-pieces, and around-the-frame winding-connections for said coils.

4. The invention as defined in claim 3, characterized by said mounting-plate having a cylindrical shape.

JOHN W. CLOKEY.
